UNITED STATES PATENT OFFICE.

WILLIAM LILISTON PARDUE, OF LENOIR CITY, TENNESSEE.

TOWEL RACK.

Application filed February 5, 1923. Serial No. 617,070.

To all whom it may concern:

Be it known that I, WILLIAM L. PARDUE, a citizen of the United States, residing at Lenoir City, in the county of Loudon and State of Tennessee, have invented certain new and useful Improvements in Towel Racks, of which the following is a specification.

This invention relates to improvements in 10 towel holders.

The primary object of this invention is the provision of a towel holder which will securely maintain a towel in position thereon against liability of accidental detachment, 15 and in such manner that the towel may be used without liability of assuming a crumpled position thereon.

A further object of this invention is the provision of a towel holder, including a novel 20 supporting frame and grips so associated thereon that the towel may be effectively maintained in secure relation upon the frame at each end thereof.

A further object of this invention is the 25 provision of a towel holder which is relatively simple in construction, economical to manufacture, and by means of which a towel may be suspended in a plurality of ways therefrom.

30 Other objects and advantages of this invention will be apparent during the course of the following detailed description.

In the accompanying drawing, forming a part of this specification, and wherein similar 35 reference characters designate corresponding parts throughout the several views.

Figure 1 is a perspective view of the improved towel holder, showing the manner in which the same retains a towel in position 40 thereon for use.

Figure 2 is a fragmentary transverse cross sectional view, showing the means of securing the towel to the towel holder.

In the drawing, wherein for the purpose 45 of illustration is shown but the preferred embodiment of this invention, the letter A generally designates the improved towel holder, which embodies a supporting frame B; and grip member C.

50 The frame B is preferably formed of a single piece of steel wire or analogous material, bent to provide the towel supporting bar 10; and upper V-shaped frame portion 11. The V-shaped frame portion 11 is 55 twisted adjacent its apex, as at 13, and upwardly of the twisted portion the triangular

shaped suspension head 14 is provided having an opening 15 which decreases in dimension from the twisted portion 13 to the extreme apex 16 of said suspension head 14. 60 From the twisted portion 13, the V-shaped frame portion 11 provides arms 17 and 18, which are in diverging relation.

The towel suspending bar 10 is preferably straight, and at one end thereof is integrally 65 connected to the free end of the arm 17 as by the bight portion 18. The free end of the arm 18 is provided with a depending loop 20, which is U-shaped and extends substantially at right angles to the plane defined by 70 the V-shaped frame portion 11. On the other hand, the free end of the supporting bar 10 is provided with an inverted U-shaped loop 21, in a plane flush with the run of the bar 10. The loops 20 and 21 are adapted for 75 detachable interconnection, in manner similar to the ordinary safety pin construction, and whereby the ends of the arm 18 and the bar 10 may be affixed to provide a stable 80 frame structure. When so connected, the arms 17 and 18 may be said to relatively converge toward the twisted portion 13; and with respect to the bar 10, the arms 17 and 18 may also be said to extend in diverging 85 relation therefrom.

Rubber grip members C are provided, which are frustoconical in formation, having the large diametered end surface 25 and the smaller diametered end surface 26 in substantially parallel relation; the outer surface 27 of each member C extending in conical uniformly increasing dimension from the reduced end surface 26 toward the larger end surface 25. It is thus to be observed 90 that these rubber members C might be 95 called wedge members. Both of said members are axially provided with axial passageways whereby the same may be slidably mounted for longitudinal adjustment upon the frame arms 17 and 18, so that they are 100 movable toward or away from the ends of said arms.

In use, a towel D has one end thereof disposed over the supporting bar 10, so that the full length of the towel may be used and 105 the rubber grip members C are slid downwardly over their respective frame arms toward the supporting bar 10, and brought into wedge engagement with the side portions of the towel B, securely clamping said 110 towel to the supporting bar 10, as can well be understood. By this means, the towel B

can be used for the full length thereof and not be of the double fold type used with the ordinary roller.

The fact that the loop portions 20 and 21 of the frame B provide a detachable feature for opening said frame, permits the use of ordinary, roller or continuous towel upon the supporting bar 10, if desired.

From the foregoing description of this invention, it is apparent that an improved towel holder has been provided, by means of which the towel may be very effectively clamped in position, where the same may be used without liability of jerking the same from its supported position upon the frame B. The fact that the triangular shaped head 14 provides the opening 15, as above described, permits the suspension of the frame in the most effective manner against liability of accidental displacement from a suspending nail or hook.

Various changes in the shape, size and arrangement of parts may be made to the form of invention herein shown and described, without departing from the spirit of the invention or the scope of the claims.

I claim:

1. As an article of manufacture, a towel support member of wire bent to provide a supporting bar, a V-shaped portion having one end thereof fixedly connected with an end of said supporting bar and the other end for detachable engagement with the other end of said supporting bar, and grip members slidable upon said V-shaped portion for adjustment toward or away from the ends of said supporting bar.

2. A device of the class described comprising a frame portion including a supporting bar, one end of which is provided with an inverted U-shaped loop, and an inverted V-

shaped portion, the apex of which provides a suspending head from which arm portions extend in diverging relation, one of said arm portions being fixedly connected to an end 45 of said supporting bar and the other arm of said V-shaped frame portion having the free end thereof provided with a U-shaped loop extending in the plane substantially at right angles to the run of the loop and adapted 50 for interengagement with the loop upon the free end of said supporting bar, and grip members slidable on the arm portions of said frame for relative movement toward or away from said supporting bar. 55

3. As an article of manufacture, a towel holder comprising a supporting bar, an arm formed at an end of said supporting bar extending in acute angular relation therewith, and a grip member slidable on said arm 60 adapted to be moved therealong so that the same may directly engage and clamp a towel or other article against said supporting bar, said grip member when moved upwardly along said arm releasing its clamping 65 action to permit removal of the towel.

4. As an article of manufacture, a towel holder comprising a supporting bar, arms connected at the ends of said supporting bar extending in acute angular relation 70 away therefrom in a converging relation, said arms being connected together at their opposite ends, and grip members slidable on each of said arms adapted to be moved therealong so that the same may directly engage and clamp a towel or other article against said supporting bar, said grip members when moved upwardly along said arms 75 adapted to release their clamping action to permit removal of the towel or other article.

WILLIAM LILISTON PARDUE.
